UNITED STATES PATENT OFFICE.

JAMES T. COWLEY, OF LOWELL, MASSACHUSETTS, ASSIGNOR TO THE LAMSON CONSOLIDATED STORE SERVICE COMPANY, OF NEWARK, NEW JERSEY.

PNEUMATIC-DESPATCH-TUBE APPARATUS.

SPECIFICATION forming part of Letters Patent No. 657,090, dated September 4, 1900.

Application filed March 23, 1899. Serial No. 710,155. (No model.)

To all whom it may concern:

Be it known that I, JAMES T. COWLEY, of Lowell, in the county of Middlesex and State of Massachusetts, have invented certain new and useful Improvements in Pneumatic-Despatch-Tube Apparatus, of which the following is a specification.

My invention relates to improvements in pneumatic-despatch-tube apparatus in which the carriers are impelled through a tube by air-pressure.

My invention consists of certain novel features hereinafter described, and particularly pointed out in the claims.

In the accompanying drawings, which illustrate a construction embodying my invention, Figure 1 shows an end elevation of one of the terminals. Fig. 2 shows a side elevation of the same. Fig. 3 is a top plan view of the terminal with the upper part removed. Fig. 4 is a sectional side elevation of the lower part of the terminal and valve-box, showing the valves and detail mechanism of the same. Fig. 5 shows an end elevation of the lower part of the terminal and valve-box. Fig. 6 shows a section of the same on the line X X, Fig. 2, looking in the direction indicated by the arrow. Fig. 7 is an enlarged side view of the hollow standard for supporting the upper curved part of the terminal. Fig. 8 is an end view of the same. Fig. 9 is a view of the switch which is operated automatically to close the circuit during the discharge of the carrier. Fig. 10 shows a section of the switch on the line X' X', Fig. 9. Fig. 11 is a side view showing the opposite ends of the line and the terminals at each end with the connections between the opposite ends broken away. Fig. 12 is a diagrammatic view of the electric circuits. Fig. 13 is a diagrammatic view similar to Fig. 12, showing the magnets and the switches at opposite ends of the line with the switches both open and no current passing. Fig. 14 is a diagrammatic view of the electric circuits, magnets, and switches and showing the right-hand switch closed and the magnets at both ends of the line energized. Fig. 15 is a diagrammatic view of the electric circuits, magnets, and switches and

showing the left-hand switch closed and the magnets at both ends of the line energized.

Like letters of reference refer to like parts throughout the several views.

When it is desired to despatch a carrier, it is inserted into the terminal at the inlet A (see Figs. 2, 4, and 11) and passes down through the opening C' of the valve-box C into the despatch-tube B. The valve D' is then closed to the position shown in dotted lines, Fig. 4, against the valve-seat C². This valve D' is pivoted to the forked lever D at D², and the upper part of this forked lever D is secured to the shaft D³, passing through the valve-box C and journaled therein. This valve-box is provided with a closed pocket E, through which the shaft D³ passes. On this shaft D³ and projecting into this closed pocket is a lever F, and bearing against the lower end of this lever F is another lever G⁶, the upper end of which is mounted loosely on the shaft G⁴, journaled in the upright ears G³ of the bottom plate G², and said lever G⁶ passes down through openings in the plates G G². The shaft G⁴, journaled in the ears G³, extends outwardly on one side and is provided with a handle G⁵ for a purpose to be hereinafter described. On this shaft G⁴ is securely fastened the forked lever G⁹, Figs. 4 and 6, provided at its outer end with the roll H, mounted on the pivot H', and against the other end of the lever G⁹ bears the lip G⁷, projecting upwardly from the lever G⁶. This lip on the lever G⁶ is held in contact with the lever G⁹ by a spring G⁸ around the shaft G⁴, the opposite ends of the spring bearing on the levers G⁶ and G⁹ and holding the lip G⁷ in contact with the lever G⁹ at all times, as shown in Fig. 4. In order that the valve D' may be closed, as above described, the handle G⁵ is moved forward toward the left from the position shown in Fig. 2, moving with it the shaft G⁴, to which the lever G⁹ is secured, and through the medium of the spring G⁸ and the lever G⁶ the lever F and the valve D' are moved to the position shown in dotted lines, Fig. 4, thereby closing the opening C' in the valve-box C, which communicates with the despatch-tube B.

Located in the pocket L and secured to the plate G is a plate K, provided with a hub K', within which is mounted the plunger J, provided at its top with the flange J', against which the roll H of the lever G⁹ bears. Within the pocket L is mounted the plunger L', held in a raised position by the spring L², as shown in Fig. 4. This plunger L' is provided with a hollow stem L³, to which the valve L⁴ is secured by the nuts L⁵, and the lower end of the valve-stem L³ has an opening L⁶ communicating with the pocket M of the valve-box C. The spring L⁷ tends to keep the plunger J in the position shown in Fig. 4. L⁸ is a flange on the stem L³ to limit the downward movement of the plunger L' in the pocket L. The plunger J is provided with a circular groove J² and a longitudinal slot J⁴ on the periphery of said plunger, which connects the circular slot J² with the upper part of the pocket L. The hub K' is provided with the vent K² in alignment with the circular groove J² when the parts are in the position shown in Fig. 4. K³ is a cushion against which the flange J' stops when pushed down by the lever G⁹, as hereinafter explained.

M' is a plate covering the bottom of the valve-box C, to which the air-pressure-supply pipe M² is secured and which communicates with the pocket M. To this plate is also secured the despatch-tube B for the transmission of carriers. The air-pressure-supply pipe M² extends between the two terminals and at a convenient point is connected with the air-supply tank M³, into which air is forced under pressure by a suitable air-pump through the pipe M⁴.

Extending upward from the plate G and secured thereto is a curved portion N of the terminal, having an opening N' for the discharge of the carriers into a suitable receptacle N². Projecting down from the portion N of the terminal is a hollow lug O, having the foot O'.

Referring to Figs. 7 to 10, inclusive, O² represents a shaft passing through the hollow lug O and having secured thereto within said hollow lug the lever O³, projected across the curved portion N of the terminal. To one end of the shaft O² is a spring O⁶, one end of which is secured to the shaft O² in the slot O⁷ and the other end is secured around the pin O¹⁰, extending from the lug O. This spring O⁶ is covered by the casing O⁴, which fits over the ring O⁵, secured to the lug O by the screws O¹¹. Secured to the opposite side of this lug O is a ring O⁸, over which the casing O⁹ fits. Within this ring O⁸ is a disk P, of hard rubber, fiber, or other non-conducting material, and seated within said disk are the metallic contact-plates P' P⁸, Figs. 9 and 10, provided with suitable binding-screws P⁷ P⁹. Located around the shaft O² is a collar P⁸, to which is secured a disk P⁴, of non-conducting material, and bearing against the disk P⁴ is the center of the switch P², the outer ends of which are

adapted to engage with the metallic contact-plates P' P⁸ when the switch is moved. P⁵ is a washer over the center of the switch, through which the screw P⁶ passes into the shaft O², 70 securely holding all the parts together.

Referring to Figs. 11, 12, 13, 14, and 15, from a suitable battery S the wire Q passes upwardly to the magnet T, supported by the plate T', (see Fig. 4,) secured to upright ears 75 G³ of the plate G². This magnet is provided with an armature T², secured to the upper end of the catch T³, pivoted at T⁴ to a vertical extension of the plate G². This catch is provided with a suitable spring-plunger T⁵, 80 which bears on the plates G² and tends to hold the catch in position to engage with the flange J' of the plunger J as the plunger descends. From the magnet T the wire Q passes up through the hollow standard R', 85 having its flange R secured to the foot O' of the lug O and having its lower flange R² secured to the plate G. The upper end of the wire Q is secured in contact with the plate P' by the binding-screw P⁷, as shown in Fig. 9. 90 The wire Q' is secured to the contact-plate P⁸ by the binding-post P⁹ and passes down through the standard R', and the wire Q' then passes off to the other end of the line to a magnet similar in construction and operation to 95 that above described and shown in Fig. 4 and used at the right hand of the drawing, Fig. 11, and said magnet (at the left hand of drawing, Fig. 11) is connected to the battery S by the wire Q. Another wire Q² is connected to the wire Q' at Q³ and passes to the terminal at the opposite end of the line and up through the standard R' to a binding-post similar in construction to that shown in Fig. 9, used at the right hand of Fig. 11. Another 100 wire Q⁵ is secured to the other binding-post of the switch and extends down through the standard R' and is connected to the wire Q' at Q⁴, as illustrated in Figs. 11, 12, 13, 14, and 15. This arrangement is for the purpose of completing the circuit and energizing the magnet at the end of the line when the switch at one end of the line is operated by the discharge of a carrier. When the apparatus is not in operation, both the switches 105 P² at the opposite ends of the line are open and, as shown in Fig. 13, no current is passing. When the switch P² at the right-hand end of the line is closed, Fig. 14, the current passes from the battery S by the wire Q to 110 the magnet T to the wire Q⁵ through the switch P² to the wire Q² to the magnet T at the left-hand end of the line and then to the battery S by the wire Q, as indicated by the arrows, the wire Q' being dead in this operation. When the switch P² at the left-hand end of the line is closed, (see Fig. 15,) the current passes from the battery S by the wire Q to 115 the magnet T at the right-hand end of the line, then by the wire Q' through the switch P² to the junction Q³ to the magnet T at the left-hand end of the line, and then by the 120

wire Q to the battery S, as indicated by the arrows, the wire Q² being dead in this operation.

The operation of the device is as follows:

- 5 A carrier is dropped into the inlet A (right hand of drawing, Fig. 11) and passes down through the opening C' in the valve-box C into the despatch-tube B, Fig. 4. The handle G⁵ is then moved to the left and closes 10 the valve D', as previously described. This movement of closing the valve also pushes down the lever G⁹, which is fast to the shaft G⁴, and this movement of the lever G⁹ carries with it the plunger J against the tension 15 of the spring L⁷. After the valve D' is closed the movement of the lever G⁹ is continued, the spring yielding and allowing the plunger J to be still further depressed. When the plunger reaches its lowest position, the catch 20 T³ will engage with the flange J' on the plunger J and hold it in its lowest position by reason of the spring-plunger T⁵. When this plunger J is in its lowest position, the ports 25 J³, communicating through the plunger J into the recess J⁵, will be in alignment with the upper part of the pocket L above the plunger L'. With the plunger in the position just described the air-pressure passes up through the opening L⁶ and through the ports 30 J³ into the upper part of the pocket L above the plunger L', and by reason of this plunger L' being of greater area than the valve L⁴ the plunger L' is forced down by the air-pressure opening the valve L⁴ and allowing 35 the air-pressure to pass from the pipe M² into the valve-box C and thence into the despatch-tube B, driving the carrier which has just been inserted to the opposite end of the line. The pressure of the air through the valve- 40 box C is sufficient to hold the valve D' in contact with the valve-seat C² upon the removal of the hand from the handle G⁵, and the plunger J being held down by the catch T³ will remain in its position, allowing the 45 air to blow through the despatch-tube B until the catch T³ is released from the flange J' on the plunger J. The carrier traveling along the tube B toward the opposite end of the line—that is, the left hand of Fig. 11—which 50 is identical in construction to the terminal shown in Figs. 1 and 2 and at the right hand of Fig. 11 will pass through the curved portion N into and out of the opening N' into the suitable receptacle. During this discharge 55 the lever O³ at the left hand of Fig. 11 will be depressed, carrying with it the shaft O² and switch P², connecting the metallic plates P' and P⁸ and forming a closed circuit which will energize the magnet T at the right 60 hand of Fig. 11 and release the catch T³ from the flange J' on the plunger J, allowing the spring L⁷ at the right hand of Fig. 11 to return the plunger J to its position, as shown in Fig. 4. This release of the plunger J will move 65 the parts J³ out of alignment with the upper part of the pocket L and will also bring the circular groove J² into alignment with the
- vent K² in the hub K' on the plate K. The longitudinal slot J⁴ in the periphery of the plunger J will in this position form a vent 70 for the upper part of the pocket L, allowing the air to escape out through the vent K². It will be seen with the parts in this position, Fig. 4, that the air-pressure from the pocket M is cut off from the upper part of the pocket 75 L and that also a vent is formed for the upper part of the pocket L to allow the escape of the air from said upper part through the vent K², when the spring L² will force the plunger L', carrying with it the valve L⁴, upwardly to the position shown in Fig. 4, closing the opening from the pocket M and preventing the further flow of air into the despatch-tube B. As soon as the air has ceased 80 to flow into the despatch-tube B the pressure 85 is removed from the valve D' and the valve will drop by gravity to its normal position, as shown in full lines, Fig. 4, at which time the apparatus is in condition for the despatching of another carrier. 90
- From the above it is clear that the air in the storage-reservoir is used only during the transit of a carrier from one terminal to another, as the air-pressure is cut off immediately upon the arrival of the carrier at the 95 opposite despatch-terminal.
- As shown and described, a single tube is used for the transit of the carrier in both directions, as the terminals and the operating parts at each end may be identical in construction and operation. 100
- The operation above described as taking place in the terminal at the right hand of Fig. 11 upon the discharge of the carrier at the left hand of Fig. 11 will likewise occur in 105 the terminal at the left hand of Fig. 11 upon the discharge of a carrier coming from the left hand of Fig. 11 and discharging at the right hand of Fig. 11.
- As a discharging-carrier is passing through 110 the terminal N it strikes the lever O³, fast on the shaft O², and puts the spring O⁶ under tension. After the carrier has passed by said lever the spring O⁶ by reason of its tension moves the lever O³ back into its normal position, as shown in Fig. 2, and in position to 115 be operated by the next carrier to close the electric circuit.
- I do not limit myself to the arrangement and construction shown, as the same may be 120 varied without departing from my invention.
- Having thus ascertained the nature of my invention and set forth a construction embodying the same, what I claim as new, and desire to secure by Letters Patent of the 125 United States, is—
1. In a pneumatic-despatch-tube apparatus, a carrier-transmitting tube having an inlet and an outlet for the carriers, a valve for closing said inlet after the insertion of the 130 carriers, a source of compressed air, mechanism for closing said valve, an air-inlet, a valve controlling said air-inlet, mechanism normally holding said valve to close said air-

inlet, mechanism for opening said air-inlet valve and arranged to be operated by compressed air from said source, means for establishing communication between said source and said mechanism to open said valve, means for controlling the flow of air from said source to said valve-opening mechanism, means for holding said air-inlet valve open, an electric circuit, circuit-closing means located in the path of the traveling carrier and arranged to be operated thereby, and an electromagnet included in said circuit and energized upon the closing of said circuit by the traveling carrier to release said air-inlet-valve-holding means to allow the closing of said air-inlet valve.

2. In a pneumatic-despatch-tube apparatus, a carrier-transmitting tube having an inlet and an outlet for the carriers, a valve for closing said inlet after the insertion of the carriers, a source of compressed air, mechanism for closing said valve, an air-inlet, a valve controlling said air-inlet, mechanism normally holding said valve to close said air-inlet, mechanism for opening said air-inlet valve and arranged to be operated by compressed air from said source, means for establishing communication between said source and said mechanism to open said valve, means controlling the flow of compressed air to said valve-opening mechanism, mechanism for operating said air-controlling means to allow the passage of compressed air, a yielding connection between said mechanism closing the valve of the carrier-inlet and the mechanism which operates the air-controlling means, means for holding said air-inlet valve open, an electric circuit, circuit-closing means located in the path of the traveling carrier and arranged to be operated thereby, and an electromagnet included in said circuit and energized upon the closing of said circuit by the traveling carrier to release said air-inlet-valve-holding means to allow the closing of said air-inlet valve.

3. In a pneumatic-despatch-tube apparatus, a carrier-transmitting tube having an inlet and an outlet for the carrier, a valve for closing said inlet after the insertion of the carriers, a source of compressed air, an air-inlet, a valve controlling said air-inlet, mechanism normally holding said valve to close said air-inlet, mechanism for opening said air-inlet valve and arranged to be operated by compressed air from said source, means for establishing communication between said source and said mechanism to open said valve, means controlling the flow of compressed air to said valve-opening mechanism, means for holding said air-inlet valve open, and mechanism located in the path of the traveling carrier and operated thereby to release said air-inlet-valve-holding means to allow the closing of said air-inlet valve.

4. In a pneumatic-despatch-tube apparatus, a carrier-transmitting tube having an inlet and an outlet for the carriers, a valve for clos-

ing said inlet after the insertion of the carriers, a lever for closing said valve, a shaft on which said lever is mounted, and a handle fast on said shaft for operating said lever to close said valve.

5. In a pneumatic-despatch-tube apparatus, a carrier-transmitting tube having an inlet and an outlet for the carriers, a valve for closing said inlet after the insertion of the carriers, a lever for closing said valve, a shaft on which said lever is mounted, a handle fast on said shaft and adapted to be moved to operate said lever to close said valve, a source of compressed air, an air-inlet, a valve controlling said air-inlet, mechanism normally holding said valve to close said air-inlet; mechanism for opening said air-inlet valve and arranged to be operated by compressed air from said source, means for establishing communication between said source and said mechanism to open said air-inlet valve, a lever carried by said shaft to operate the means for establishing communication between the source of compressed air and the mechanism for opening the air-inlet valve, means for holding said air-inlet valve open, and mechanism located in the path of the traveling carrier and operated thereby to release said air-inlet-valve-holding means to allow the closing of said air-inlet valve.

6. In a pneumatic-despatch-tube apparatus, a carrier-transmitting tube having an inlet and an outlet for the carriers, a valve for closing said inlet after the insertion of the carriers, a source of compressed air, an air-inlet for the compressed air, a valve controlling said air-inlet, means for moving said valve to close said air-inlet, a pocket, a hollow stem supporting said valve controlling the air-inlet and forming a passage between said source of compressed air and said pocket, and a plunger mounted in said pocket having an area larger than that of said valve controlling the air-inlet and connected with said stem and adapted to be moved by the pressure of air in said pocket to open said valve controlling the air-inlet.

7. In a pneumatic-despatch-tube apparatus, a carrier-transmitting tube having an inlet and an outlet for the carriers, a valve for closing said inlet after the insertion of the carriers, a source of compressed air, an air-inlet for the compressed air, a valve controlling said air-inlet, means for moving said valve to close said air-inlet, a pocket communicating with said source of compressed air, and a plunger mounted in said pocket and connected with said valve controlling the air-inlet and having an area larger than that of the valve controlling the air-inlet and adapted to be moved by the introduction of compressed air into said pocket to open said valve controlling the air-inlet.

8. In a pneumatic-despatch-tube apparatus, a carrier-transmitting tube having an inlet and an outlet for the carriers, a valve for closing said inlet after the insertion of the car-

riers, a source of compressed air, an air-inlet for the compressed air, a valve controlling said air-inlet, means for moving said valve to close said air-inlet, a pocket communicating with said source of compressed air, a plunger mounted in said pocket and connected with said valve controlling the air-inlet and having an area larger than that of the valve controlling the air-inlet and adapted to be moved by the introduction of compressed air into said pocket to open said valve controlling the air-inlet, and means for regulating and controlling the flow of compressed air into said pocket.

15 9. In a pneumatic-despatch-tube apparatus, a carrier-transmitting tube having an inlet and an outlet for the carriers, a valve for closing said inlet after the insertion of the carriers, a source of compressed air, an air-inlet 20 for the compressed air, a valve controlling said air-inlet, a pocket, a hollow stem supporting said valve controlling the air-inlet and forming a passage between said source of compressed air and said pocket, a plunger 25 carried in said hollow stem for regulating and controlling the passage of air through said stem, means for moving said plunger, and a second plunger mounted in said pocket having an area larger than that of the valve controlling the air-inlet and connected with said stem and adapted to be moved by the pressure of air in said pocket to open said valve controlling the air-inlet.

10 10. In a pneumatic-despatch-tube apparatus, a carrier-transmitting tube having an inlet and an outlet for the carriers, a valve for closing said inlet after the insertion of the carriers, a source of compressed air, an air-inlet for said compressed air, a valve controlling 35 said air-inlet, mechanism normally holding said valve to close said air-inlet, mechanism for opening said valve and arranged to be operated by compressed air from said source, means for establishing communication 40 between said source and said mechanism to open said valve, means controlling the flow of compressed air to said valve-opening mechanism, and mechanism located in the path of the traveling carrier and operated 45 thereby to allow the closing of said air-inlet valve.

11 11. In a pneumatic-despatch-tube apparatus, a carrier-transmitting tube having an inlet and an outlet for the carriers, a valve for closing said inlet after the insertion of the carriers, a source of compressed air, an air-inlet for said compressed air, a valve controlling 50 said air-inlet and provided with a hollow stem open to said compressed air and with a plunger mechanism normally holding said valve to close the air-inlet of greater area than the valve, a plunger movable in said hollow stem and having passages for leading the compressed air to one side of the 55 said plunger of greater area than the valve to open said valve by the pressure acting on said plunger of greater area, mechanism for

closing said carrier-inlet valve and for moving said plunger in said stem to establish the said communication for the compressed air, 70 means for holding said plunger located in the hollow stem to maintain said communication for the compressed air to hold said air-inlet valve open, mechanism located in the path of travel of the carriers and operated by the latter to release the air-inlet valve from the mechanism holding it open, and means for returning said plunger to its normal position.

12. In a pneumatic-despatch-tube apparatus, a carrier-transmitting tube having an inlet and an outlet for the carriers, a valve for closing said inlet after the insertion of the carriers, a source of compressed air, an air-inlet for the compressed air, a valve controlling said air-inlet and provided with a hollow stem 85 open to the said compressed air and with a plunger of greater area than the valve, mechanism normally holding said valve to close the air-inlet; a plunger movable in said hollow stem and having passages for leading the 90 compressed air to one side of the plunger of greater area than the valve to open said valve by the pressure acting on said plunger of greater area, mechanism for closing said carrier-inlet valve and for moving said plunger 95 in said stem to establish the said communication for the compressed air, means for holding said plunger located in said hollow stem to maintain said communication for the compressed air to hold said air-inlet valve open, 100 an electric circuit, circuit-closing means located in the path traveled by the carriers and operated by the latter, an electromagnet included in said circuit and adapted to be energized upon the closing of said circuit to release 105 said air-inlet-valve-holding means to allow the closing of said air-inlet valve, and means for returning said plunger to its normal position.

13. In a pneumatic-despatch-tube apparatus, a carrier-transmitting tube having an inlet and an outlet for the carriers, a valve for closing said inlet after the insertion of the carriers, an air-inlet, a valve controlling said air-inlet, mechanism normally holding said 115 valve to close the air-inlet; a source of compressed air, mechanism operated by compressed air for opening said air-inlet valve, means controlling the flow of compressed air to said valve-opening mechanism, means for holding said air-inlet valve open, an electric circuit, circuit-closing means located in the path traveled by the carriers and operated by the latter, an electromagnet included in said circuit and adapted to be energized upon 125 the closing of said circuit to release said air-inlet-valve-holding means to allow the closing of said air-inlet valve, and means for returning said circuit-closing means into the path of the carrier for breaking said electric 130 circuit.

14. In a pneumatic-despatch-tube apparatus, a carrier-transmitting tube having an inlet and an outlet for the carriers, a valve for

closing said inlet after the insertion of the carriers, an air-inlet, a valve controlling said air-inlet, mechanism normally holding said valve to close said air-inlet; a source of compressed air, mechanism for opening said air-inlet valve and arranged to be operated by compressed air from said source, means for establishing communication between said source and said mechanism to open said valve, means controlling the flow of compressed air to said valve-opening mechanism, means for holding said air-inlet valve open, an electric circuit, a circuit-closing means located in the path traveled by said carriers and operated by the latter, an electromagnet included in said circuit and energized upon the

closing of said circuit by the traveling carrier to release said air-inlet-valve-holding means to allow the closing of said air-inlet valve, and a spring for automatically returning said circuit-closing means into the path of the carrier and for breaking said electric circuit. 20

In testimony whereof I have signed my name to this specification, in the presence of 25 two subscribing witnesses, this 17th day of March, A. D. 1899.

JAMES T. COWLEY.
